UNITED STATES PATENT OFFICE

2,469,637

UMBRELLA FRAME

Wayne S. Evans and Louis G. Tartaglia, Philadelphia, Pa., assignors to S. W. Evans & Son, Philadelphia, Pa.

Application August 29, 1946, Serial No. 693,703

4 Claims. (Cl. 135—30)

1

The object of the invention is to provide improvements in umbrella and parasol frames, reference especially being made to the wireless type of frame, wherein no wires are employed for pivotally securing the inner ends of the ribs and stretchers indirectly to the shaft, or directly to the usual notch and runner mounted thereon, so as to thereby produce a better structure at less cost, and at the same time one that is more easily repaired, as well as one in which the breaking of a single hinge element does not release all of the ribs or stretchers, as has heretofore usually been the case.

Another and more specific object is to provide in frames of this character, which will herein-after be referred to by the generic term of umbrella frames, annular attaching members for subsequent mounting upon the umbrella shaft, called notches or runners as the case may be, each of said members comprising a pair of telescoped, cylindrical elements, provided with a slotted L-shaped flange having circumferentially spaced slots, and the other being provided with an initially conical flange also having circumferentially spaced slots of the same number and position as the slots of said first flange, said latter flange when bent into a plane at right angles to the common axis of said members to enclose an annular space between said members which is wholly enclosed except for said slots, a ring within said space having circumferentially spaced recesses in alignment with the pairs of slots in said flanges, and a rib or stretcher end portion extending radially into said space through said slots and having trunnions that prevent the escape of said end from within said recess, said ring taking the radially inward thrust upon said rib or stretcher, while the sides of the ring's recesses operating to prevent lateral shifting or turning of said rib or stretcher other than in a plane coincident with the axis of said notch or runner and the shaft which is surrounded thereby.

With the objects thus briefly set forth, the invention comprises further details of construction and operation, which are hereinafter fully brought out in the following description, when read in conjunction with the accompanying drawings, in which Figs. 1 and 2 are, respectively, the plan and side elevations, the latter being partially in section, of the inner shell or tubular member of the improved notch or runner construction; Figs. 3 and 4 are corresponding views of the improved ring; Figs. 5 and 6 are similar views of the improved outer shell or tubular telescoping member of said notch or runner; Fig. 7

2

is a longitudinal section of the three elements of Figs. 1 to 6 in assembled relation but before the initially conical flange of the inner shell or tubular member is flattened against the intervening ring; Fig. 8 is similar to Fig. 7 but showing the end portion of a rib or stretcher in operative position and the last-mentioned flange flattened in final position; Fig. 9 is a front elevation of the assembly shown in Fig. 8 partially broken away; and Fig. 10 is a plan of a ring that is modified to the extent of having more peripheral recesses than the ring shown in Figs. 3 and 9.

Referring to the drawings, it is to be understood that the structure shown in the drawings represents either a notch or runner, for while the proportion of its length to its diameter is that of a notch, the only difference between it and a runner to which the invention is applied is in its length and incorporation of any suitable means for yieldingly maintaining such runner in a given position upon the usual shaft. Accordingly, the alternative term "notch or runner" will be used to designate the fact that the invention is equally well adapted to each of them, and for want of a generic term.

The inner shell, as shown per se in Figs. 1 and 2, comprises a cylindrical portion 1, having circumferentially spaced lugs or ears 2, initially extending from it in one longitudinal direction. In the opposite direction there initially extends a diagonally outwardly directed flange 3, having a series of circumferentially spaced, radially extending slots 4, which are ten in number for a ten-rib umbrella, or sixteen in number for a sixteen-rib umbrella, though only a representative eight slots are shown for purposes of illustration.

In Figs. 3 and 4 is shown a plane ring 5 having a central aperture 6 of sufficient size to receive the outer diameter of the cylindrical portion of the inner ring. The outer periphery of this ring is broken by a series of equally spaced, preferably rectangular recesses or cut-outs 7, each of which has a radially inwardly projecting, preferably rectangular central extension 8 of less width than the major outer portion of the cut-out.

The size and shape of these recessed cut-outs substantially conform to the shape of the radially inner end portions of the ribs and stretchers 9 of an umbrella frame, each of which latter in the improved invention comprises a flattened portion 10, from the laterally opposite sides of which extend the ends 11 of a pin or rivet, which

serve as trunnions about which the rib or stretcher oscillates angularly.

Referring to Figs. 8 and 9, it will be seen that the extreme end of the flattened portion 10 of the rib or stretcher is positioned in the inner cut-out extension 8, when the umbrella frame is in open or extended position, while at the same time the trunnions 11 are positioned in the laterally opposite portions 7a of the recess 7.

In Figs. 5 and 6 is shown the improved outer shell, which comprises a cylindrical portion 12 of such internal diameter as to slidably receive telescopically the corresponding portion 1 of said inner shell, after which the lugs or ears 2 are deflected radially outwardly (Figs. 7 and 8) to prevent accidental separation of said shells following assembly. The opposite end of said outer shell merges into a planular section 13, which thence terminates in a cylindrical extension 14, the outer diameter of which is substantially equal to that of the flange 3 of the inner shell when the latter is flattened into its final form (Figs. 8 and 9).

Circumferentially spaced slots 15 extend inwardly from the outer free edge of said flanges 13 and 14 to a depth having substantially the same diameter as that of the inner ends of the slots 4 in the flange 3 of said inner shell (Figs. 7 and 8). Also it will be noted as an essential condition of the invention, that the axes of the inner and outer shell slots 4 and 15 and the intervening ring cutouts 7-8 must be in alignment, in order to provide for and insure free oscillation of the ribs or stretchers positioned therein.

Referring to Fig. 10, there is shown a slightly modified form of ring 16, having an axial bore 17, corresponding to the bore 6 in the ring 5, and outwardly directed, circumferentially spaced cutouts 18, which construction is primarily designed for use in a standard sixteen-rib umbrella frame, or one of sufficiently more ribs than can be provided for by the construction shown in Figs. 1-9. In this case, the end of the rib or stretcher alone enters a cutout 18 and finds there what may be termed a thrust-bearing, while the trunnions of the rib or stretcher ride or oscillate upon the peripheral surface 19 of said ring, upon the opposite sides of the particular cutout into which the end of the rib or stretcher extends.

By either of these arrangements, the final assembly of the two shells, ring and rib or stretcher is maintained, without the slightest tendency of either of the flanges 3 and 14 to be deflected away from their respective operative positions, while in general a more rigid and resultingly permanent structure is insured.

Having thus described our invention, what we claim and desire to protect by Letters Patent of the United States is:

1. In an umbrella frame, a notch or runner construction comprising an inner shell having a cylindrical portion and a radially slotted plane flange, an outer shell comprising a cylindrical portion in telescopic relation to the corresponding portion of said inner shell and also a plane flange having a cylindrical extension, said last-mentioned flange and its extension being provided with spaced slots in registry with the slots of said inner shell flange, the flanges of said shells defining an annular space between them, and a ring within said space having cutouts aligned

with said slots, the sides of said cutouts functioning as thrust bearings for a rib or stretcher extending through said slots into said annular space.

5. 2. In an umbrella frame, a notch or runner construction comprising an inner shell having a cylindrical portion and a radially slotted plane flange, an outer shell comprising a cylindrical portion in telescopic relation to the corresponding portion of said inner shell and also a plane flange having a cylindrical extension, said last-mentioned flange and its extension being provided with spaced slots in registry with the slots of said inner shell flange, the flanges of said shells defining an annular space between them, and a ring within said space having cutouts aligned with said slots, each cutout having a central extension, in combination with a rib or stretcher extending through said slots into said annular space and carrying oppositely projecting trunnions, the end of said rib or stretcher extending into said central cutout extension while said trunnions engage the walls of said cutout upon the opposite sides of said extension.
10. 3. In an umbrella frame, a notch or runner comprising the combination of a pair of telescopic members enclosing an annular space and having circumferentially spaced apertures through which the end portions of ribs or stretchers extend into said space, each of said ribs or stretchers being provided with oppositely extending trunnions, which prevent said end portions from being freely withdrawn from within said annular space, and an annular ring within said space provided with cutouts to slidably receive the ends of said ribs or stretchers and prevent them from shifting angularly in the plane in which said trunnions extend.
15. 4. In an umbrella frame, a notch or runner comprising the combination of a pair of telescopic members enclosing an annular space and having circumferentially spaced slots through which extend the end portions of ribs or stretchers, each of said ribs or stretchers being provided with oppositely extending trunnions, which prevent said end portions from being freely withdrawn from within said annular space, and an annular ring within said space provided with circumferentially spaced cutouts to receive the end portions of said ribs or stretchers and said trunnions, and each cutout having a radially inward extension to receive the end only of said rib or stretcher beyond said trunnions, said inward extension being operative to prevent angular shifting of said rib or stretcher in the plane in which lie said trunnions, and the widened outer portions of said cutouts being operative as bearings for said trunnions.
